UNITED STATES PATENT OFFICE.

HORACE R. SIMMS, OF RACINE, WISCONSIN, ASSIGNOR TO AMERICAN SKEIN & FOUNDRY COMPANY, OF RACINE, WISCONSIN, A CORPORATION OF WISCONSIN.

METHOD OF AND APPARATUS FOR MAKING MOLDS FOR CASTING PIANO-PLATES.

1,131,743.

Specification of Letters Patent. Patented Mar. 16, 1915.

Application filed September 28, 1914. Serial No. 863,964.

To all whom it may concern:

Be it known that I, HORACE R. SIMMS, a citizen of the United States, residing at Racine, in the county of Racine and State 5 of Wisconsin, have invented certain new and useful Improvements in the Method of and Apparatus for Making Molds for Casting Piano-Plates, of which the following is a specification.

10 My invention relates to the manufacture of cast piano plates and its object is to make an improvement in the method of and apparatus employed in preparing the molds for casting such plates.

15 A piano plate of the type in which this invention is concerned consists of a skeleton casting provided with pins to which the strings of the piano are attached. In the past it was the general practice to first cast 20 the plates and afterward drill holes in them in which the pins were set. As the drilling of a large number of holes in a casting is a costly and laborious operation, the attempt has been made to unite the pins with the 25 plate during the casting operation. At first the ends of the pins were simply embedded in the green sand of the mold, the pattern being formed so as to hold the pins in proper position while the sand was being rammed 30 around them. This method of procedure was not successful because when the pattern was removed from the mold, as, for example, in forming the mold in the molding machine, which is the most expeditious 35 and economical manner of making molds of this sort, the pins were likely to be disturbed or pulled out of their places by the movement of the pattern. To overcome this it has been proposed to support the pins by 40 stationary rods on which the projecting ends of the pins rest. These rods pass up through perforations in the pattern so that the pattern slides upon the same when lowered. This method, however, is open to the objection 45 that the rods, which are necessarily slender, are likely to become bent more or less, in which case the lowering of the pattern causes a springing or lateral displacement of the rods as a result of which 50 the pins are frequently dislodged from the

green sand or are loosened so that when the flask is removed from the molding machine they fall out or at least do not occupy the intended vertical position. Furthermore, according to this method, after the pattern 55 has been lowered the pins are held in place in the mold only by the relatively weak adhesion of the green sand so that they are quite likely to be displaced during the subsequent handling of the mold. 60

The principal object of my invention is to improve upon the manufacture of piano plates having string supporting pins cast therein, by providing a method of preparing the mold by means of which the pins are 65 reliably and accurately held in their proper positions in the mold as against any tendency to follow the pattern or to be otherwise displaced during the lowering of the pattern or subsequent thereto. 70

A further object is to provide a novel method of forming apertures in the plate for the keys to which the piano strings are attached and by the turning of which the strings are given the proper pitch in tuning. 75 It was formerly customary to mount these pins outside of the metal piano plate upon the wood structure to which the plate was attached. In order to utilize the plate for bracing the keys it has been more recently 80 the practice to extend the plate somewhat and drill apertures in the extension through which the keys project. My invention provides a method of forming these apertures during the casting operation, thereby saving 85 the expense of drilling which is considerable.

I apprehend that my invention involves not only the novel improvements in the method of preparing the molds above referred to, but also certain improvements in molding machinery for carrying out said process, to which improvements I also desire to lay claim herein. 90

The accompanying drawings illustrate the 95 improvements constituting my invention as employed in connection with a molding machine in which the pattern is withdrawn, by suitable apparatus, from the mold after the sand has been rammed.

Figure 1 is a view, in perspective, of a molding machine of this type, the pattern of which is constructed in accordance with my invention. Fig. 2 is a plan view of one member of the flask, the drag, with the mold formed therein. Fig. 3 is a view, in perspective, of the finished piano plate. Fig. 4 is a perspective view of one of the dry sand cores used for positioning the string supporting pins in the mold. Fig. 5 is a similar fragmentary view of the core box in which a core, such as that shown in Fig. 4, is molded. Fig. 6 is a similar view illustrating the construction of a core box 15 for a core having a single row of pins. Fig. 7 is a cross sectional view of the core and core box shown in Fig. 6, inverted and with the members separated one from the other for the purpose of removing the core. Fig. 20 8 is a vertical sectional view taken through the pattern and mold showing one of the cores and the pins embedded therein. Fig. 9 is a similar sectional view on line 9—9 of Fig. 1. Fig. 10 is a view, corresponding to Fig. 9, showing the pattern withdrawn 25 from the mold. Fig. 11 is a sectional view through the dry sand core and adjacent portions of the pattern illustrating a modified arrangement for positioning the core on the 30 pattern.

Like characters of reference designate like parts in the several figures of the drawings.

The molding machine shown as a whole in Fig. 1 is, in its general design, of familiar 35 construction consisting of a supporting structure 25, a stripping plate 26, and a pattern 27 which is raised and lowered by means of the link and toggle mechanism 28 operated by a hand lever 29.

40 The finished piano plate, designated 30 (Fig. 3), is shown as provided with a single row of pins 31 cast into the rib 32 and a double row of pins 31^a cast into the rib 33. The plate has a flat, thin extension 34 formed 45 with a number of apertures 35 through which extend keys (not shown) to which the piano strings are secured. It will be obvious that the design of the plate might be materially changed without departure from my invention, such modifications involving corresponding changes in the pattern and in the construction and arrangement of the dry sand cores employed for holding the pins in 50 position in the mold. One of these dry sand cores, namely, one of the cores with the single row of pins, together with the core box in which it is molded, is illustrated in Figs. 6 and 7. The core box is made in two sections 36, 37, and is formed in the bottom 55 60 with perforations 38 adapted to receive the pins 31, the line of parting between the sections passing through the perforations. After the pins have been put in place the core box is filled with a body of material 39 suitable

for forming a dry sand core. After the core 65 has been molded in this way the sections are separated and the core, with the pins embedded therein, is baked in the usual manner. The core is preferably wider at its inner face than across the face in which the 70 pins are fixed so that when in the mold it resists any tendency to follow the pattern when the latter is lowered. The core 40 (Fig. 4), which supports the double row of pins 31^a, is similarly molded in a core box 75 made up of three sections, 41, 42, 43, having a double row of perforations 44, the lines of separation between the sections extending through these perforations. The core sections thus formed, with the pins firmly embedded therein, are placed upon the pattern before the green sand is rammed, with the pins projecting downwardly through suitable apertures. For example, I have shown the ribs of the pattern formed with elongated slots or recesses 45 into which the pins extend. The core sections are held in position on the pattern against displacement by any suitable means. In Fig. 8 I have shown two of the pins designed to be cast into the plate, namely, the pins designated 31^b at the extremities of the core section 40, as extending into perforations 46 in the pattern. In the modified arrangement illustrated in Fig. 11 the pattern, designated 47, is formed with a slot 48 long enough to include all of the pins here designated 31^c, and is provided with upstanding dowels 49 which enter holes in the ends of the core designated 50.

After the cores are in position the green 100 said 51 is rammed around the pattern and the cores so that the latter are firmly embedded in the mold. The pattern may then be lowered without danger of disturbing the pins. The slots in the pattern are preferably 105 made wide enough so that there is no danger of the pins binding therein. The arrangement, it will be seen, is much superior to that in which each pin is positioned in a 110 separate hole in the pattern because by in this manner eliminating possible binding between the pins and pattern, there is much less danger that the withdrawal of the pattern will disturb the pins or the cores in which they are embedded.

115 The apertures 35 for the keys are made as follows: Dry sand cores 52, 53, assuming that the perforations 35 are grouped as shown in Fig. 3, are formed with circular nubs 54 projecting from one side thereof for 120 a distance equal to the thickness of the extension 34 of the piano plate. These cores are molded with the nubs thereon in any suitable manner. The pattern corresponding to this part of the plate is formed with 125 recesses 55, 55^a, having a depth equal to the projection of the nubs, and the cores are placed on the pattern, before the green sand

- is rammed, with the nubs in these recesses (Fig. 9). The cores may be held in position by any suitable means, for example, by wires 56 attached to cross pieces 57 on the drag 58.
- 5 The other member of the mold, that which is formed on the core, may, generally speaking, have any desired configuration. The part overlying the nubs 54 will, however, be formed to come in close contact with said 10 nubs so that when the iron is poured the nubs will form the apertures 35 of the casting.

The purpose of the elements described as "dry sand cores" is to provide an adhesion 15 between the mold and the pins which is much greater than that afforded by the green sand. At the same time, the cores must be of such material that they may be broken away or otherwise stripped from the pins after the 20 casting is made. By the term "dry sand cores" I intend cores or holding elements for the pins adapted to be embedded in the green sand constituting the body of the mold which will have the qualities just mentioned.

25 The exact composition of the cores is unimportant.

I claim:

1. The method of preparing a mold for casting a piano plate and uniting thereto 30 during the casting operation pins for the piano strings, which consists in arranging on a pattern, apertured to receive the extremities of said pins, a dry sand core in which the other extremities of the pins are 35 embedded, ramming green sand around the pattern and said dry sand core, and then separating the pattern and mold.

2. The method of preparing a mold for casting a piano plate and uniting thereto 40 during the casting operation pins for the piano strings, which consists in arranging on a pattern, formed with an elongated slot to receive the extremities of a plurality of said pins, a dry sand core in which the other 45 extremities of the pins are embedded, ramming green sand around the pattern and said dry sand core, and then separating the pattern and mold.

3. The method of preparing a mold for casting a piano plate and uniting thereto 50 during the casting operation pins for the piano strings, which consists in arranging the pins in proper spaced relation in holes in a multiple part core box, the lines of separation 55 between the parts of which pass through said holes, filling the core box with a material suitable for making a dry sand core, separating the core box from the core and baking the core, then placing said dry 60 sand core on a pattern, apertured to receive the extremities of the pins, ramming green sand around the pattern and said dry sand core, and then separating the pattern and mold.

4. The method of preparing a mold for 65 casting a piano plate and uniting thereto during the casting operation pins for the piano strings, which consists in arranging on a pattern, apertured to receive the extremities of said pins, a core in which the pins 70 are firmly fixed, ramming green sand around the pattern and said core, and then separating the pattern and mold.

5. The method of preparing a mold for casting piano plates having apertures for 75 the keys to which the piano strings are attached, which consists in forming a pattern for the plates with a recess of a depth as great as the thickness of the apertured portion of the plate, making a dry sand core 80 formed with nubs having the configuration of said apertures and projecting from one side of the core a distance equal to the thickness of the plate, placing said core on the pattern over the recess with the nubs 85 turned toward the pattern, ramming green sand around the pattern and the dry sand core so that the latter is embedded in the mold and then separating the pattern from the mold.

6. In a molding machine for making piano plates, the combination with a supporting structure and stripping plate, of a pattern and means for moving the same toward and away from the stripping plate, 95 said pattern being formed with an elongated slot adapted to receive the extremities of a plurality of pins designed to be united to the plate in the casting operation, and provided also with means for positioning 100 on the pattern a core in which the other extremities of the pins are embedded.

7. In a molding machine for making piano plates, the combination with a supporting structure and stripping plate, of a pattern and means for moving the same toward and away from the stripping plate, 105 said pattern being formed with an elongated slot adapted to receive the extremities of a plurality of pins designed to be united to the plate in the casting operation, and provided also with means at opposite ends of said slot for positioning on the pattern 110 a core in which the other extremities of the pins are embedded.

8. The method of preparing a mold for casting a piano plate and uniting thereto during the casting operation pins for the piano strings, which consists in arranging on a pattern, apertured to receive the extremities of said pins, a core of a shape to be anchored in the green sand of the mold against the tendency to be pulled therefrom by the pattern, in which core the other extremities of the pins are fixed, ramming 120 green sand around the pattern and core, and then separating the pattern and mold.

9. In a molding machine for making

piano plates, the combination with a supporting structure and a stripping plate, of a pattern and means for moving the same toward and away from the stripping plate, said pattern being apertured to receive the extremities of a plurality of pins designed to be united to the piano plate in the casting operation, and provided also with means

for positioning on the pattern a core in which the other extremities of the pins are 10 embedded.

HORACE R. SIMMS.
